(57) CLAIM

The ornamental design for a multiple-shelf assembly, as shown and described.

DESCRIPTION

A multiple-shelf assembly having four shelves integrally attached to four pillars.

FIG. 1 is a perspective view of multiple-shelf assembly;

FIG. 2 is a front view thereof;

FIG. 3 is an enlarged top plan view of the pillar portion thereof;

FIG. 4 is a bottom plan view of the pillar portion thereof;

FIG. 5 is a right side view thereof; and,

FIG. 6 is a rear view thereof.

1 Claim, 4 Drawing Sheets

FIG. 1

FIG. 2

FIG. 3

FIG 4

FIG. 5

FIG. 6
